UNITED STATES PATENT OFFICE.

HORACE D. STEVENS, OF AKRON, OHIO, ASSIGNOR TO THE FIRESTONE TIRE AND RUBBER COMPANY, OF AKRON, OHIO, A CORPORATION OF OHIO.

TUBE-SPLICING MACHINE.

Application filed March 15, 1923. Serial No. 625,310.

This invention relates to the art of manufacturing inner tubes for pneumatic tires or the like, although it is not necessarily so limited but may have a broader application. In 5 the manufacture of these articles, it is customary to vulcanize the tube into a single length with the ends of the tube free. It is then necessary to unite the two ends of the tube to make it continuous or endless. 10 It is the purpose of this invention to construct an apparatus which will facilitate the insertion of the one end of the tube within the other. This act is usually performed after both ends of the tube have been buffed 15 and cemented and while the cement is in a sticky or tacky condition, and the machine includes means for expanding one end of the tube and maintaining it in expanded condition, while the other end is being inserted in 20 position, at the same time providing a simple and effective means for preventing contact of the prepared surfaces of the tube until the ends are in the desired position.

The apparatus here shown will assist materially in the operation of joining the ends of the tube and has advantages of simplicity in construction and operation.

In the drawings accompanying this application one form or embodiment of the invention is shown, it being obvious that other forms may be made without departing from the essential features of the invention as described and claimed.

In the drawings:

35 Figure 1 is a side elevation of a tube splicing apparatus constructed in accordance with the invention;

Figure 2 is a front elevation of the upper or working parts of the device;

40 Figure 3 is a plan view;

Figure 4 is a cross-section on the line 4—4 of Figure 3; and

Figure 5 is a section on the line 5—5 of Figure 1, showing the manner in which the 45 two ends of the tube are nested.

The apparatus shown herein comprises a base or platform 1 which, for convenience of operation, may be mounted on rollers or casters 2, so that it can be moved about the shop 50 to the location of the tubes to be spliced.

From the platform 1 rises an upright 3 which supports a table 4 which carries the working portions of the apparatus, an upright arm or stand 5 at the rear thereof being designed to support the main portion of the tube being 55 operated upon.

To the upper surface of the table 4 is secured a base plate 6 to which are attached two brackets 7, the arms of which extend upwardly at a slight forward inclination to the base. 60 To the upper ends of the arm is secured a rod or bar 8 which in turn carries a horizontal guide plate 9, the upper surface of which is formed with a recessed guideway 10. A second rod or bar 11 is secured to the under 65 side of the plate 9 in parallel relationship to the bar 8.

Slidably mounted in the guide plate 9 is a reciprocable slide 12, depending from the under side of which is a pin 13 which passes 70 through a slot 14 in the plate 9. The pin 13 is received in any one of a number of holes 15 formed in a plate 16, which extends parallel to the slide 12 and is formed with sockets 17 at its ends. A rope or cable 18 is secured 75 to the socket at one end of the plate 16 and a second rope or cable 19 is attached to the other socket.

The rope 18 passes over a sheave or pulley 20 supported in downwardly curved arms 21 on the bars 8 and 11 and thence over a pulley 22 supported in brackets 23 on the base plate 6, to an adjustable link 24, which is attached to a foot treadle 25, pivoted on the base 1. The cable 19 passes over a pulley 26, located 80 similarly to the pulley 20 but at the opposite side of the apparatus and is attached to a coil spring 27, which is also secured to the base. The arrangement is such that the slide 12 is maintained at the left hand end of the 85 guideway or at its extreme expanded position, but can be moved to the right or contracted position by operation of the foot treadle.

To open up one end of the tube, two pairs of fingers are provided, one pair of which is rigid with the guide plate and the other pair of which is secured to the slide. The construction of these fingers is substantially the same. Each comprises a straight arm 28 95

and a second arm 29 above and parallel thereto, the second arm being carried from the first by a U-shaped bracket 30 and having a stop 29^a to regulate the position of the tube. On the sides of each arm at the points where the tube is engaged are rollers 31, so that the tube may be readily withdrawn from the arms. The outward movement of the slide is regulated by a stop pin 32, which may be adjusted in any one of the holes 33 on the side of the guide and which pin contacts the member 28 on the slide.

In the operation of the device, the end of the tube, which is to be positioned exteriorly of the other in the making of the splice and which is buffed and cemented on its interior surface, is placed over the fingers, which have been caused to approach one another by the operation of the foot treadle. The treadle is now released and the spring brings the fingers to their expanded position as determined by the pin 32. This end of the tube is now held open and the other end of the tube is inserted and the treadle is again depressed, permitting the outer end of the tube to contract over the inner. The tube may now be withdrawn from the fingers, the rollers 31 permitting and assisting in such movement.

It is advisable to prevent contact of the outer cemented surface of the entering tube end with the inner surface of the receiving tube end until they are in the desired position. For this purpose I make use of a novel and simple form of shield or deflector such as shown in the drawings. This comprises a light, flexible sheet metal plate 34 which is preferably attached to the rigid fingers and is so formed that it has a permanent bend therein, the free end of the plate projecting under the movable fingers. The tendency of the shield 34 is to bend or arch upwardly, as shown in Figures 2 and 5, at whatever position the expanding fingers are located, and this upward bending affords an effective shield or deflector for the tube. By this means the entering tube end is elevated above the receiving tube end so that contact between the ends of the tube is prevented.

It is believed that the operation of the device will have been apparent from the description which has been given. The apparatus assists to a considerable degree in the assembling of the ends of the tube, the fingers holding the receiving end of the tube expanded until the other end enters therein. The deflector acts as a shield to prevent contact of the tube ends until the proper moment for release of the expanded end. The device is adjustable by the various means described to operate upon all sizes of tubes.

It is obvious that changes and modifications may be made in forms of the invention, but, as I believe I am the first to provide an apparatus of the character set forth in

which the splicing of the tube is rendered easy and rapid, the claims hereto appended should be given a wide range of equivalents for the purposes specified.

What I claim is:

1. In a machine for the uses and purposes set forth, the combination with a base plate, of a pair of tube engaging members and means to cause said member to separate to hold the end of the tube distended and unobstructed to receive the other end of the tube therein.

2. In a machine for the uses and purposes set forth the combination with a base plate, of tube end engaging means adapted to be inserted within the open end of a tube and separated to distend the end of the tube in position to receive the other end of the tube therein, and means to hold said members apart after the tube has been placed over them.

3. In a machine for the uses and purposes set forth, the combination with a base, of tube end engaging fingers insertible within the end of the tube and movable toward and away from one another, yielding means adapted to hold the fingers in their furthest expanded position, and adjustable limiting means for determining the expanse of said fingers.

4. In a machine for the uses and purposes set forth, the combination with tube end engaging fingers, of means to separate said fingers in a lateral direction and a shield projecting between the fingers in front of one edge of the tube.

5. In a machine for the uses and purposes set forth, the combination with tube end engaging fingers, of means to separate said fingers in a lateral direction and an arcuate flexible shield projecting between the fingers in front of one edge of the tube.

6. A machine for the uses and purposes set forth, comprising the combination of tube end engaging fingers, means to separate said fingers in a lateral direction, yielding means to hold said fingers at their outer limits, and a flexible metal shield attached to one of said fingers bending upward in front of one edge of the tube and depressed by the other finger.

7. In a machine for splicing inner tubes, the combination of a base plate, tube end engaging fingers insertible within the end of the tube and movable toward and away from one another, rollers on the fingers, and means to move the fingers.

8. A machine of the class described, having in combination, means to distend one end of a tube in position to receive the other end of the tube therein, and means to prevent contact between the two ends until they are properly positioned.

9. A machine of the class described, having in combination, means to engage the end of a tube, and means to move said engaging

means to distend the end of the tube in position to receive the other end of the tube therein.

10. A machine of the class described, having in combination, means to engage one end of a tube, and means to move said engaging means laterally to open up the engaged end and provide a passageway in which the other end of the tube may be positioned.

11. A machine of the class described, having in combination, means adapted to be inserted within one end of a tube, and means for moving said means to distend the end of the tube so that the other end of the tube may be inserted between the distending means and 15 into the distended end of the tube.

HORACE D. STEVENS.
